US00D860168S

(12) **United States Design Patent** (10) **Patent No.:** **US D860,168 S**
(45) **Date of Patent:** **** Sep. 17, 2019**

(54) **SPEAKER**

(71) Applicant: **SHENZHEN LEADINGPLUS ELECTRONIC CO., LTD.**, Shenzhen (CN)

(72) Inventor: **Jun Yang**, Shenzhen (CN)

(73) Assignee: **SHENZHEN LEADINGPLUS ELECTRONIC CO., LTD.**, Shenzhen (CN)

(**) Term: **15 Years**

(21) Appl. No.: **29/643,381**

(22) Filed: **Apr. 8, 2018**

(51) LOC (12) Cl. **14-01**

(52) U.S. Cl.

USPC **D14/216**; D14/215

(58) **Field of Classification Search**

USPC D14/167, 168, 170–172, 188, 194–196, D14/204, 207, 209.1, 210–216, 219, 221, D14/222, 224, 239, 496; 181/143, 144, 181/147, 148, 150, 153, 157, 198, 199; 381/300–303, 306, 332, 333, 336, 345, 381/361–364, 386–388; 369/6–12

CPC B60R 11/0217; G06F 1/1688; G10K 9/22; G10K 11/004; H03F 1/327; H04M 1/03; H04M 1/035; H04N 5/642; H04N 21/4852; H04R 1/02; H04R 1/06; H04R 1/021; H04R 1/025; H04R 1/026; H04R 1/028; H04R 1/105; H04R 1/323; H04R 1/403; H04R 1/2803; H04R 1/2834; H04R 5/02; H04R 7/20; H04R 9/06; H04R 9/025; H04R 2201/021; H04R 2400/00; H04R 2400/07; H04R 2499/11;

H04R 2499/13; H04R 2499/15; H04S 3/00; H04S 7/30

(57) **CLAIM**

The ornamental design for a speaker, as shown and described.

DESCRIPTION

FIG. 1 is a front perspective view of a speaker.

FIG. 2 is a back perspective view of the speaker.

FIG. 3 is a front view of the speaker.

FIG. 4 is a rear view of the speaker.

FIG. 5 is a top view of the speaker.

FIG. 6 is a bottom view of the speaker.

(Continued)

FIG. 7 is a side view of the speaker; and,
FIG. 8 is an opposite side view of the speaker.

1 Claim, 8 Drawing Sheets
